CLAIM

The ornamental design for a pouch for a portable electronic communication device, as shown and described.

DESCRIPTION

FIG. 1 is a front view of a pouch for portable electronic communication device according to the present invention.

FIG. 2 is a rear view of the pouch of FIG. 1.

FIG. 3 is a right side view of the pouch of FIG. 1.

FIG. 4 is a left side view of the pouch of FIG. 1.

FIG. 5 is a top view of the pouch of FIG. 1.

FIG. 6 is a bottom view of the pouch of FIG. 1.

FIG. 7 is an enlarged, fragmented cross-sectional view taken along line 7—7 of the pouch of FIG. 1.

FIG. 8 is a front perspective view of the pouch of FIG. 1; and, FIG. 9 is an open front perspective view of the pouch of FIG. 1.

The broken line showing of a hand is included for the purpose of illustrating environment and forms no part of the claimed design.
